UNITED STATES PATENT OFFICE.

HARRIET N. GRAY, OF AUSTIN, TEXAS, ASSIGNOR OF ONE-HALF TO GEORGE E. GRAY, OF SAME PLACE.

ABDOMINAL SUPPORTER.

SPECIFICATION forming part of Letters Patent No. 895,050, dated December 25, 1888.

Application filed September 14, 1888. Serial No. 285,407. (No model.)

To all whom it may concern:

Be it known that I, HARRIET N. GRAY, a citizen of the United States, residing at Austin, in the county of Travis and State of Texas, have invented certain new and useful Improvements in Abdominal Supporters; and I do hereby declare the following to be a full, clear, and exact description of the invention, such as will enable others skilled in the art to 5
10 which it appertains to make and use the same, reference being had to the accompanying drawings, and to letters or figures of reference marked thereon, which form a part of this specification.

15 The object of my invention is to provide an abdominal supporter which shall retain its proper position on the person of the wearer and can be worn with ease and comfort, the abdomen being supported without any undue 20 strain or pressure; and to this end the invention consists of the improved supporter hereinafter described and claimed.

In the accompanying drawings, Figures 1 and 2 are front and rear views, respectively, 25 of my improved abdominal supporter.

A is a waist-belt buttoned in front and made with the broad back piece, A', covering what is called the "small" of the back. Suspended from the waist-belt in front by the elastic 30 straps or tapes *a* there are two abdominal pads, B. These pads are sector-shaped, with the apex of the sector at the side and the curved edges adjacent in front. They are connected in front by straps and a buckle, *b*, and 35 are stiffened with whalebones let in vertically between the two thicknesses of cloth forming the pads. The back piece, A', of the belt is also stiffened with whalebones, as shown. Buttoned to the bottom of this back belt-piece 40 there are two broad straps, C, which pass under and button in front to the lower corners of the abdominal pads B. These straps C are made quite broad at their rear ends, and then

taper to narrow straps. Buttoned to these straps there may be a catamenial sack, D, or 45 the straps may support and hold in place a napkin during the menstrual periods. Attached to the side corners of the abdominal pads there are straps E, which pass round the hips and button to the short straps of elastic 50 webbing, E', fastened or buttoned to the pieces C.

The elastic straps *a a* and *E' E'* taken together give all the play necessary to adapt the supporter to the changes of the figure due to 55 change of position. It can be worn without any inconvenience, but with comfort and relief, as a uniform and equal support is given to the abdomen.

Buttoned to the front and rear of the waist-belt there are tabs F and G, respectively, to which are buttoned the elastic shoulder-straps H. After child-birth the shoulder-straps may be discarded and the supporter worn with comfort for several months or more, or as long 65 as desired.

Having thus described my invention, what I claim as new, and desire to secure by Letters Patent, is—

The abdominal supporter herein described, 70 consisting of the waist-belt, the abdominal sector-shaped pads hung from the waist-belt by elastic straps, the straps C, buttoned to the belt behind and to the bottom of the abdominal pads in front, the side straps connecting 75 the abdominal pads with the pieces C at the back, and the front strap connecting the two abdominal pads together with the shoulder-straps, all substantially as and for the purpose set forth.

In testimony whereof I affix my signature in presence of two witnesses.

HARRIET N. GRAY.

Witnesses:

JOE ARMSTRONG,
E. F. McCARTY.
